Patented Mar. 13, 1917.

UNITED STATES PATENT OFFICE.

JOHN H. N. PETERSON, OF BAKER, OREGON.

SHOE-FASTENING DEVICE.

1,219,146.

Specification of Letters Patent. Patented Mar. 13, 1917.

Application filed November 16, 1916. Serial No. 131,735.

To all whom it may concern:

Be it known that I, JOHN H. N. PETERSON, a citizen of the United States, residing at Baker, in the county of Baker and State 5 of Oregon, have invented certain new and useful Improvements in Shoe-Fastening Devices; and I do declare the following to be a full, clear, and exact description of the invention, such as will enable others skilled in 10 the art to which it appertains to make and use the same.

This invention relates to new and useful improvements in fasteners, and the primary object of the invention is to provide a fastener for securing the opposing margins of 15 a shoe, in a quick and efficient manner.

Another object of the invention is to provide a device of this character which is easily and simply constructed, inexpensive to man- 20 ufacture and one which will be very efficient in operation.

With these and other objects in view the invention consists of the novel features of construction, combination and arrangement 25 of parts as will be herein referred to and more particularly pointed out in the specification and claims.

In the accompanying drawings:

Figure 1 is a perspective view of a shoe 30 showing my improved fastener securing the margins thereof together;

Figs. 2, 3 and 4 are detail views of one of the fasteners showing its different positions during the locking operation with respect to 35 the margin of the shoe;

Fig. 5 is a longitudinal section through the margins showing the fastener in closed position when the said margins are disposed above each other; and,

Fig. 6 is a similar view showing the fastener in the other or locked position.

In describing my invention I shall refer to the drawings in which similar reference characters designate corresponding parts 45 throughout the several views. The fastener is formed from a single piece of metal designated by the numeral 1 having a spear shaped enlarged button plate 2 which has one end thereof designated by the numeral 3 pointed and extending downwardly. The outer surface of the plate 2 is roughened by providing the same with a plurality of transversely extending closely spaced grooves as shown at 3'. Projecting from the opposite 50 end of the plate 2 is a narrow integral strip 4 which extends a short distance in a single

plane of this plate and is then bent back upon itself as shown at 5.

The strip 4 extends forwardly beneath the plate 2 and has its free end 6 bent upwardly and secured to the plate. This securing means is optional and preferably the plate is formed with an opening therein designated by the numeral 7 and the extremity of the end 6 is positioned therein and secured in any desired manner. This bending of the strip will form an elongated longitudinally extending loop that is disposed beneath the plate 2. This loop extends from a point past the rear end of the plate to adjacent the front pointed end of the same, and substantially to where this last mentioned end of the plate starts to bend downwardly.

The strip 4 is formed of some spring metal and the lower portion of the loop formed thereby which is designated by the numeral 8 is bowed upwardly intermediate its ends to form a lock which will be herein-after more fully described.

This fastener is held in position on the margin 9 of a shoe by means of an eye 10 which is secured thereto by having its free ends bent downwardly as shown at 11 and secured in the material of the margin, or having the said free ends sewed thereto. It is essential that the eye 10 project upwardly from the margin. The other margin of the shoe which is designated by the numeral 12 is provided with a button hole 13 therein which is substantially in alinement with the fastener when the same is in position. In use the eye 10 is positioned in the elongated loop disposed beneath the button plate 2 as clearly shown in Fig. 2 of the drawings.

In operation when the fastener is secured to the margin 9 of the shoe and it is desired to fasten the other margin in overlapped relation therewith, the eye 10 is positioned at the rear end of the elongated loop whereupon the plate 2 may swing upwardly to the position shown in Fig. 2 of the drawings. When in this position the margin 12 of the shoe is brought over and is disposed above the margin 9, and the plate 2 and loop are projected through the button hole 13 in said overlapping margin, as shown in Fig. 3. Owing to the fact that the elongated loop extends past the top plate at the rear end of the same, this plate may swing freely so that when in this position the plate is swung forwardly again and down over the over-

lapping margins as clearly shown in Fig. 4 of the drawings.

To securely lock the fastener in position the eye 10 in the loop is moved from the rear to the front end of the same over the bowed portion 8 in the lower side of said loop, by forcing the top plate 2 upwardly along said eye until the parts assume this position. When the plate and loop have been moved along until the eye is at the front of said loop, the downwardly bent front end 3 of the top plate will securely engage the adjacent edge and the margin 12 and lock the parts in position. The relation of the different parts of this device when in this position is clearly shown in Fig. 6 of the drawings.

The bowed portion 8 of the elongated loop formed by the bent strip, forms a lock, so that the eye 10 will be securely held either at the front or rear of the loop. When the eye is at the rear of the loop, the top plate may swing freely but when it is disposed at the front of the same it will be impossible to move the plate and the same will securely lock the margins of the shoe together. This bowed portion, owing to the fact that the strip is formed of spring metal, will not allow the eye to move along the loop except under pressure, as the portion of the eye through the loop is wider than the space between the top of the bowed portion and the bottom of the button plate. The button plate may be easily moved along the eye from the position shown in Fig. 5 of the drawings to the position shown in Fig. 6 by engaging the downwardly bent front end of the same and pushing rearwardly thereon. To unfasten the margins the operation above described is reversed. The button plate is drawn through the button hole when in proper position. The roughened outer surface 3' of the plate 2 allows said plate to be moved easily backward, as the plate may be securely gripped by the operator's thumb or finger, for movement, without any likelihood of slipping therefrom.

From the foregoing description of the construction and operation of my improved shoe fastening device, the manner of applying the same and the operation thereof will be readily understood, and it will be seen

that I have provided a simple and efficient means for carrying out the objects of the invention.

55

I claim:

1. The combination with a pair of members to be secured together and adapted to be disposed in overlapped relation, the upper member having a hole, and an upstanding eye on the lower member, of a button plate comprising a flat metal plate having one end tapered and bent downwardly, a narrow integral strip projecting from the opposite end of the large portion of the plate and being bent back upon itself beneath the button plate with its free end projecting upwardly and connected to the plate at the juncture of the flat and downwardly bent portions to form an elongated resilient loop, said loop having its intermediate portion bowed inwardly toward the bottom of said plate and spaced therefrom, thereby forming an enlarged loop at each end, said enlarged loops being in a plane with the end of the tapered portion of the plate, whereby when the device is in locked position, the enlarged loops will contact the aforesaid upper member and said end of the tapered portion will bear against the edge of the said upper member to keep it in close contact with the lower member.

2. A device of the class described comprising a button plate formed from a single piece of metal with one end pointed and bent downwardly, a narrow integral strip projecting from the opposite end of the plate and bent back upon itself, said strip extending beneath the button plate with its free end projecting upwardly and connected with the plate to form an elongated loop disposed beneath said plate adapted to engage a stationary eye, and the lower portion of said strip beneath the plate being resilient and bowed to form a lock for the eye.

In testimony whereof I have hereunto set my hand in the presence of two subscribing witnesses.

JOHN H. N. PETERSON.
